UNITED STATES PATENT OFFICE.

HERBERT O. RUSSELL, OF DETROIT, MICHIGAN, AND CHARLES LEIGH PAULUS, OF DAYTON, OHIO.

FLARE BRACKET.

Application filed April 18, 1922. Serial No. 555,406.

To all whom it may concern:

Be it known that we, HERBERT O. RUSSELL and CHARLES LEIGH PAULUS, citizens of the United States, residing, respectively, at Detroit and Dayton, in the counties of Wayne and Montgomery and States of Michigan and Ohio, have invented certain new and useful Improvements in Flare Brackets, of which the following is a specification.

This invention relates to flare brackets, the object in view being to produce a flare bracket for carrying landing flare candles upon an airplane or aircraft of any kind, the said brackets being designed to hang or be carried close to the wing and present a minimum amount of head resistance.

A further object of this invention is to provide in conjunction with the flare bracket, a reflector which not only aids in the illumination of the ground but which also deflects the heat from the machine itself. By means of the reflector, the light from the candle is thrown downwardly in a line substantially at a right angle to the wing, which, when the airplane is landing, is tilted at a stalling angle of about 20 degrees. This throws all of the light from the candle in a forward and downward direction which is very desirable. The device also contains a safety mechanism, which in the case of a bad landing will trip the candle, throwing the same to the rear and thereby eliminating danger of fire.

In the drawings;

Figure 1 is a vertical section through the flare bracket.

Figure 2 is a bottom plan view of the same.

Figure 3 is an end view thereof.

Referring to the drawings, 1 designates a mounting bracket which is adapted to be secured to an aircraft and preferably to the bottom of one of the wings thereof. The bracket comprises a housing 2 designed to receive one end of a flare candle 3 which is held in place by means of a clamping ring or band 4.

The band 4 is of such size as to encircle and firmly hold the flare candle 3 and the end portions 5 and 6 of said clamping band are extended and holes are formed therein to receive a clamping bolt or pin 7 threaded and carrying a winged nut 8 so that the desired tension may be placed on the clamping band 4 to securely hold the candle. Mounted

on the shaft or pin 7 is a trip lever 9 adapted to come in contact with the ground for relaxing the band 4 and permitting the candle 3 to be ejected by means of an ejector spring 10 contained within the housing 2 and under compression when the candle 3 is in place.

The trip arm 9 is formed with a cam 11 that cooperates with another cam 12 on a collar 13 on the shaft or pin 7. When the parts are in their operative position the cams 11 and 12 are in engagement with each other and serve to maintain the band 4 in clamping relation to the candle. When however, the trip arm 9 strikes the ground, the cams 11 and 12 are disengaged, thereby relaxing the band 4 whereupon the candle 3 is thrown clear of the airplane by means of the spring 10.

In the rear end of the housing 2 there is mounted an insulator 14 through which pass wires (not shown) by means of which the candle is electrically ignited. A mica heat-proof reflector 16 extends over and upon both sides of the candle 3 serving to direct the light rays downwardly while at the same time deflecting the heat away from the airplane.

Having thus described our invention, we claim:

1. A flare bracket embodying a supporting member adapted for attachment to an aircraft, a housing on said support adapted to hold a flare candle, candle ejecting means in said housing, clamping means for holding the candle against the ejecting action of said ejecting means, and a trip arm for releasing said clamping means, operable on contact with the ground.

2. A flare bracket embodying a supporting member adapted for attachment to an aircraft, a housing on said support adapted to hold a flare candle, candle ejecting means in said housing, clamping means for holding the candle against the ejecting action of said ejecting means, and a trip arm for releasing said clamping means, operable on contact with the ground, said clamping means embodying a flexible candle embracing band.

3. A flare bracket embodying a supporting member adapted for attachment to an aircraft, a housing on said support adapted to hold a flare candle, candle ejecting means in said housing, clamping means for holding

- the candle against the ejecting action of said ejecting means, and a trip arm for releasing said clamping means, operable on contact with the ground, said clamping means embodying a flexible candle embracing band, said trip arm having a camming action with said candle embracing band.
4. A flare bracket adapted for attachment to an aircraft, including a candle holding means and a second means for releasing the candle operable by contact with the ground.
5. A flare bracket adapted for attachment to an aircraft, including a candle holding means, a second means for releasing the candle operable by contact with the ground, and a third means for ejecting the candle from said first means.
6. A flare bracket adapted for attachment to an aircraft, including a candle holding means, spring means for ejecting the candle from said first means, and means for releasing said spring means by contact with the ground.

In testimony whereof we affix our signatures.

HERBERT O. RUSSELL.
CHARLES LEIGH PAULUS.
